UNITED STATES PATENT OFFICE.

MARCEL COLLIN, OF PARIS, FRANCE.

CONVERTER FOR THE SEPARATION OF THE FIXED AND VOLATILE METALS IN
COMPLEX ORES.

Specification of Letters Patent.

Patented July 16, 1912.

1,033,062.

Application filed April 4, 1911. Serial No. 618,916.

To all whom it may concern:

Be it known that I, MARCEL COLLIN, a citizen of the Republic of France, and a resident of 38 Rue Vignon, Paris, France, have invented a new and useful Converter for the Separation of the Fixed and Volatile Metals in Complex Ores, of which the following is a specification.

The present invention has for its object 10 a converter the characteristic feature of which is that it is elliptical or oval in shape, its chimney being located on the same side of the minor axis of the ellipse as the blower. This arrangement permits of effecting the 15 complete separation of the fixed and volatile metals contained in the complex ores treated in the converter.

In the accompanying drawing:—Figure 1 is a side elevation of the converter. Fig. 2 is a plan view thereof. Fig. 3 is an elevation at right angles to the first, and Fig. 4 is a section on the line 4—4 in Fig. 2.

The converter A of elliptical form is movable in the ordinary manner around trunnions *a a* by means of toothed sectors *B* and gearing *b c* operated by cranks *d* or by a chain or other suitable transmission. It receives the air from the blower through a conduit *e f* opening into an air chest *g* arranged on the same side of the ellipse as the chimney *F*, that is to say, slightly below the latter.

g designates the twyters that are arranged horizontally, preferably in two or even three tiers in order to distribute the air more uniformly throughout the entire height of the mass to be treated.

This converter operates in the following manner: The crude and granulated ores are introduced with coke into the converter after the latter has been kindled with a small quantity of fuel. This charging is preferably effected by arranging the chimney above the middle of the apparatus with the object of avoiding accumulations of material at one of the sides. A violent current of air is then supplied through the twyters and the mass becomes fused. The volatile constituents such as sulfur, arsenic, oxids of lead, 45 oxid of zinc and so forth pass up the chimney and can be collected by any suitable means. The fixed portions such as silicate

of iron, cuprous compounds and precious metals remain in the converter. By inverting the converter these fixed portions can be 55 collected in tubs or trucks *H* by decantation.

The elliptical form of the converter and the arrangement of the blower with horizontal twyters on the same side as the chimney insure such a circulation of air that it 60 passes tangentially in front of the chimney thereby avoiding any projection of fixed materials so that the blower only carries off the volatile materials in the draft.

What I claim and desire to secure by Letters Patent of the United States is:—

1. A converter having a reaction chamber elliptical in vertical cross section, with the long axis of the ellipse horizontal in the normal position of the converter, a series of 70 twyters extending from end to end of the chamber and opening horizontally into the lower portion of the latter from one side only, together with a chimney arranged midway between the ends of the chamber and opening 75 thereto substantially vertically above the twyters, for the purpose described.

2. A traveling converter having a wheel-supported frame, end uprights thereon, a trunnion-supported converter journaled on 80 said end uprights, the reaction chamber of said converter being elliptical in vertical cross section, with the long axis of the ellipse horizontal in the normal position of the converter, a series of twyters extending from end 85 to end of the chamber and opening horizontally into the lower portion of the latter from one side only, means for leading an air blast through said hollow trunnion to the twyters, a chimney arranged midway between the ends of the chamber and opening 90 thereto substantially vertically above the twyters, together with means journaled in said side frames to tilt the converter to discharge the charge through the chimney, substantially as described.

In testimony whereof I have signed my name to this specification, in the presence of two subscribing witnesses.

MARCEL COLLIN.
